Daniel Colestock INVENTOR

BY

ATTORNEY.

UNITED STATES PATENT OFFICE.

DANIEL COLESTOCK, OF TITUSVILLE, PENNSYLVANIA.

DESIGN FOR A RADIATOR.

SPECIFICATION forming part of Design No. 20,443, dated January 6, 1891.

Application filed September 20, 1890. Serial No. 365,678. Term of patent 7 years.

To all whom it may concern:

Be it known that I, DANIEL COLESTOCK, a citizen of the United States, residing at Titusville, in the county of Crawford and State of Pennsylvania, have invented and produced a new and original Design for the Ornamentation of Steam or Hot-Water Radiators, of which the following is a specification, reference being had to the accompanying drawing, forming part thereof.

My design is particularly intended for the ornamentation of sectional radiators, the sides presenting the appearance of a series of vertical columns and the end of the radiator an even or ribbed surface. The engraving herewith presented shows a face view of the outer

side of one end section and a perspective view of an entire radiator of twelve sections having angular or semi-octagon tops not intended for any additional cap or covering to the sections. The sections are all ornamented on the top with embossed or depressed figures, leaving the sides plain. The outer side of the end section is also ornamented by embossed or depressed figures. 25

I claim as my invention—

The design for the ornamentation of a radiator, as herein shown and described. DANIEL COLESTOCK.
